UNITED STATES PATENT OFFICE.

JOSHUA ADAM DILL, OF FREDERICK, MARYLAND, ASSIGNOR TO CHARLES F. KREH, OF SAME PLACE.

SHUTTER-BOWER.

SPECIFICATION forming part of Letters Patent No. 394,253, dated December 11, 1888.

Application filed May 23, 1888. Serial No. 274,835. (No model.)

To all whom it may concern:

Be it known that I, JOSHUA ADAM DILL, a citizen of the United States, residing at Frederick, in the county of Frederick and State 5 of Maryland, have invented a new and useful Improvement in Shutter Bowers and Locks, of which the following is a specification.

The invention relates to improvements in shutter bowsers and locks. Heretofore shutter-bowers have been constructed with a slotted or channeled plate that is attached to the sill of a window, a bracket that is fastened to the shutter, and a connecting-rod having one end pivoted to the bracket and the other end 15 provided with a finger-pin adapted to slide in the slotted plate and engage notches in the plate to secure the shutter in a certain position; but great difficulty is experienced in these shutter-bowers, owing to the fact that 20 the connecting-rod can be secured only at the points along the plate that are provided with the notches. Again, sometimes the shutter sags or swells, and it is found that the locking-rod will not for this cause engage any of 25 the notches, and hence it is impossible to lock the shutter when closed.

The object of the present invention is to obviate the above objection and to provide a shutter-bower in which the connecting-rod 30 may be secured with great rapidity, convenience, and certainty at any position along the slotted plate attached to the sill.

Furthermore, my invention is designed to lock the shutter when closed, the screw being 35 employed to clamp the rod G and hold the shutter from being opened from the outside. In all the devices employing notches, where only a "stated" adjustment can be made should ice or snow clog in between the shutter and the jamb, or should the hinge of the 40 shutter be loose, allowing the shutter to sag, or should the shutter swell, the connecting-rod will be found not to engage in any of the notches, and thus it will be practically impossible to lock the shutter while this state of 45 things exists.

In my invention I dispense with notches, and hence can lock the connecting-rod at any point.

50 The invention consists in the novel combination and arrangement of the parts herein-

after fully described, illustrated in the drawings, and pointed out in the claims.

In the drawings, Figure 1 is a perspective view of a shutter-bower constructed in accordance with this invention, showing it applied in position. Fig. 2 is a vertical longitudinal sectional view taken on the line *a-a* of Fig. 1.

Referring to the drawings, A designates a window-sill, to which is secured a slotted or channeled plate, B, by means of screws that pass through screw-eyes in the projections *b*. The plate B, that is secured to the window-sill A, is provided with a longitudinal slot or channel, *b'*, extending its entire length. The plate B is preferably constructed of cast metal, and the top *b*² projects a slight distance over the groove *b'*, to prevent a set-screw, C, having an elongated head, *b*³, being withdrawn from the longitudinal slot or channel *b'*.

The set-screw C, which is provided with the elongated head *b*³, is inserted through the elongated slot or channel *b'* from the under side of the plate B, and it is adapted to slide back and forth in the elongated slot or channel *b'*; and to secure it at any point along said slotted or channeled plate B a thumb-knob, D, is provided, which is bored out and internally 80 screw-threaded to engage the screw and clamp it to the said slotted or channeled plate B.

A bracket, E, is secured to the inner face of the shutter F when the latter is closed, and has a depending pivot, *e*, by means of which 85 a connecting-rod, G, having an eye, *g*, formed in each of its ends, is pivoted to said bracket E. The other end of the connecting-rod G has an eye or opening, *g'*, through which is passed the set-screw C, by means of which 90 and the thumb-knob D the end of the connecting-rod G may be secured by simply turning the thumb-knob D to any point along the slotted or channeled plate B. A washer, H, is used to prevent the wearing and consequent destruction of the connecting-rod.

From the foregoing description the construction and operation will be readily understood, and it will be obvious that shutter-bowers constructed as described are capable of rapid 100 and convenient adjustment to secure the shutter at any desired position.

I am aware that various devices have been employed to operate shutters, and I therefore wish it to be understood that I lay no broad claim to any of the features shown in this application, but limit myself to the elements as claimed. The main point claimed in this application is the attachment of the rod G. This rod can be removed from the screw; and, furthermore, as the inner end of this rod is provided with an eye to fit over the screw, the thumb-knob bears on the inner end of said rod and clamps it down upon the plate B. Thus it will be seen that the inner end of the rod G serves the function of a clamping-washer, to more securely clamp the rod to the plate B and lock the shutter in the desired position. Being designed also as a lock for the shutter, it is of course necessary that the rod G should be firmly clamped in position, and this clamping action is secured by means of the inner end of the rod G bearing upon the upper end of the plate B and pressed in contact by the thumb-knob.

Having described the invention, I claim—

25 In a shutter bower and lock, the bracket E,

adapted to be secured to a shutter; a slotted or channeled plate, B, designed to be fastened to a window-sill, a set-screw, C, inserted through the elongated slot of the plate B from the under side thereof, and having a head, b^3 , fitting 30 within the plate B, the latter being raised slightly above the sill, so as to allow the travel of the head b^3 , said head being greater in diameter than the width of the slot of the plate, and the connecting-rod G, pivoted to the 35 bracket E, and having an eye, g' , at its inner end, through which eye is passed the set-screw, and the removable thumb-knob D, fitted on the screw C and binding against the inner end of the rod G to clamp the latter upon the 40 plate B, whereby the rod G is removable from the plate B and can be clamped at any point thereof, as set forth.

In testimony that I claim the foregoing as my own I have hereto affixed my signature in 45 presence of two witnesses.

JOSHUA ADAM DILL.
